UNITED STATES PATENT OFFICE.

JOSEPH JOHNSYN, OF DORCHESTER, MASSACHUSETTS.

FOLDING BED.

1,392,169.

Specification of Letters Patent. Patented Sept. 27, 1921.

Application filed January 27, 1921. Serial No. 440,425.

To all whom it may concern:

Be it known that I, JOSEPH JOHNSYN, a citizen of the United States, and resident of Dorchester, county of Suffolk, State of Massachusetts, have invented an Improvement in Folding Beds, of which the following description, in connection with the accompanying drawing, is a specification, like characters on the drawing representing like parts.

This invention relates to folding beds and it has for one of its objects to provide a novel folding bed in which the bed bottom is hinged to the cabinet section so as to swing about an axis extending longitudinally of the bed instead of transversely thereof.

Another object of the invention is to provide a novel folding bed in which the bed bottom is made in sections, one of which constitutes the front of the cabinet, and others of which constitute the ends of the cabinet when the bed is folded.

Other objects of my invention are to provide various improvements in folding beds all as will be more fully hereinafter set forth.

In order to give an understanding of my invention I have illustrated in the drawings a selected embodiment thereof, which will now be described after which the novel features will be pointed out in the appended claims.

Figure 1 is a perspective view of a bed embodying my invention, said view showing the bed folded.

Fig. 2 is a front view showing the bed opened.

Fig. 3 is a view similar to Fig. 2 showing the bed partly folded.

Fig. 4 is a section on the line 4—4, Fig. 2.

Fig. 5 is a detail sectional view through one of the hinges.

Fig. 6 is a section on the line 6—6, Fig. 5.

Fig. 7 is a section on the line 7—7, Fig. 6.

Fig. 8 is a detail showing the brace for one of the end sections of the bed bottom.

My improved bed comprises a cabinet element and a bed element, the latter being so constructed that when the bed is folded the bottom of the bed forms both the front and the ends of the cabinet. The cabinet element is shown generally at 1 and it comprises a back 2, a bottom 3 and a top 4 which is hinged to the back as shown at 5. The

cabinet element, may, if desired, be provided with legs 6.

The bed element comprises a bed bottom on which a mattress is supported, and this bed bottom is made in sections, said sections being indicated at 7, 8 and 9 respectively. The section 7 is a central section which is hinged to the cabinet and which forms the front of the cabinet when the bed is folded, and the sections 8 and 9 are end sections which are hinged to the central section at 10 so as to fold up at right angles thereto and which constitutes the ends of the cabinet when the bed is folded. The mattress is also made in sections, it comprising the central section 11 and the two end sections 12, said sections corresponding in size to the size of the bed bottom sections. The central mattress section 11 is supported on a suitable spring structure 13 which forms part of the central bed bottom section 7, and the end mattress sections 12 are supported on a flexible support 14 in the nature of canvas, each support being fastened at one end to an end section and the other to a central section.

The bed bottom is pivotally supported by two posts 15 which form an integral part of the cabinet structure. These posts are situated at the front corners of the cabinet and terminated at the point 16.

While any suitable hinge construction between the bed bottom and the posts may be employed, I prefer that shown in Fig. 5, wherein each post is provided at its upper end with a plate 17 having an aperture 18 therein which forms at the upper end of the plate a fulcrum portion 19, and the bed bottom 7 has the hinge member 20 secured thereto which is formed with the portion 21 that partially embraces the fulcrum portion 19.

The hinge members 20 are secured to the bed bottom section 7 at a point a distance from the edge 22 equal to the height of the posts. This is shown best in Fig. 4. As a result when the bed bottom 1 is folded the lower portion 22 thereof will fold against the inside of the posts 15 and the edge 22 thereof will reach to the bottom of the cabinet. Thus the entire front of the cabinet consists of the bed bottom 7.

In folding the bed, the end mattress sections will first be folded over onto the central mattress section 11 as shown in Fig. 3. Then the bed-bottom section 7 may be folded into its vertical position as shown in dotted

- lines Fig. 4, and the end bed-bottom sections 8 and 9 are then folded in a position at right angles to the central section 7. The dimension of the end bed-bottom sections 8 and 9 is such that when the bed is folded they extend from the front to the rear wall of the cabinet and from the top to the bottom thereof, thus providing the end walls of the cabinet.
- 10 For supporting the bed when it is in its unfolded or open position I propose to employ legs 23 which are hinged to the bed bottom section 7 and which may be swung down into vertical position. These legs 23 are constructed so that when the bed is to be folded they may be swung into the position shown in Fig. 3, in which position they lie alongside of the front edge of the bed bottom section 7.
- 15 I have herein shown a construction wherein these legs 23 are connected to the bed-bottom sections 8 and 9 so that the legs and the end bed-bottom sections will be folded simultaneously. Each leg 23 is pivoted to the bed-bottom section at 24 and it is connected by a link 25 to a lever 26 pivoted intermediate of its ends to the bed-bottom section 7 at 27. The lever 26 is connected by another link 28 to the end bed-bottom section and this linkage is so proportioned that when the legs are folded into the position shown in Fig. 3, the end sections 8 and 9 will be folded up into a position at right angles to the bed-bottom section 7.
- 20 35 29 indicates stops carried by the bed bottom section 7 and on which the links 28 rest when the end bed-bottom sections are opened out, said stops limiting the outward swinging movement of said bed-bottom upward sections. In order to further brace the end sections 8 and 9 I propose to employ a link 30 on the back side of each section similar to the link 28, said link being connected to the bed-bottom section by a shorter link 31.
- 25 40 45 A stop 32 is employed on which the link 30 rests similar to the stop 29. Each end section is thus supported at both edges when it is opened.
- I have provided means for concealing the 50 hinges 21 when the bed is folded. This is accomplished by means of two sliding panels 33 which are slidably secured to the bed bottom 7 at the ends and which are constructed to overlie and conceal the hinges when the bed is folded. These sliding panels are shown as provided with screws 34 operating in slots 35 formed in a plate 36 that is set into a recess into the bed bottom 7. The lower end of each panel 33 is shaped to cover 55 the hinge portion 21 as shown in Fig. 5, and, if desired, it may have a more or less ornamental appearance so as to more perfectly conceal any joint at the lower end of the panel. When the bed is let down the 60 panels 33 move automatically upwardly so

as to clear the posts 15 as the bed is swung down into horizontal position, as shown in dotted lines Fig. 4.

I have herein shown a hook 37 secured to the back 2 and adapted to hook into an eye 38 secured to the top 4, thereby to hold the top in its open or elevated position.

Inasmuch as the bed bottom is made in sections as shown, the total length of the folded bed bottom is considerably less than 75 the full length of the bed and this has the advantage that when the bed is folded, the cabinet thus formed has a less length than the bed. This is desirable, because it enables the cabinet to be placed in locations in 80 a room where it would not be possible if the cabinet were the full length of the extended bed.

Another feature of the invention lies in the fact that the bed bottom swings in from 85 its closed to its open position about an axis extending longitudinally of the bed rather than transversely thereof. The advantage of this is that the total height of the cabinet could be only as great as the width of the 90 bed and this is also an advantage. My invention therefore enables the bed to be folded up into a very compact space so that the cabinet which is produced when the bed is folded is a relatively small one. 95

I claim.

1. In a folding bed, in combination, a cabinet element and a bed bottom element hinged thereto to fold about an axis extending longitudinally of the bed, said bed bottom element comprising a central section and two end sections hinged thereto, said central section forming the front of the cabinet and the end sections forming the ends of the cabinet when the bed is folded. 100

2. In a folding bed, in combination, a cabinet element comprising a back and having two supporting posts at its front extending part way from the bottom to the top, and a bed bottom element comprising 110 a central section hinged to said posts, and two end sections having a hinged connection with the ends of the central section and forming the head and foot of the bed bottom. 115

3. In a folding bed, in combination, a cabinet element comprising a back and having two supporting posts at its front, and a bed bottom element comprising a central section hinged to said posts, and two end 120 sections having a hinged connection with the ends of the central section and forming the head and foot of the bed bottom, said central section forming the front of the cabinet and the end sections forming the ends of the 125 cabinet when the bed is folded.

4. In a folding bed, in combination, a cabinet element, a bed bottom element pivoted to the cabinet element to fold about an axis extending longitudinally of the bed, 130

5 said bed bottom element comprising a central section and two end sections hinged to the central section, said central section forming the front of the cabinet and the 5 end sections forming the ends of the cabinet when the bed is folded, legs pivoted to the central section to support the bed in open position, a lever pivoted to each end of the central section, a link connecting each 10 lever with the corresponding end section, said levers and links operating to cause the legs to fold into a position parallel to the central section when the end sections are

folded into right angular relation to the central section.

15 5. In a folding bed, in combination, a cabinet element having two supporting posts, a bed bottom element hinged to said posts and when folded forming the front of the cabinet, and sliding panels carried by the 20 bed bottom element for covering the hinges when the bed is folded.

In testimony whereof I have signed my name to this specification.

JOSEPH JOHNSYN.
